UNITED STATES PATENT OFFICE.

LINNAEUS E. BAKER, OF FORT WAYNE, INDIANA, ASSIGNOR TO WAYNE COMPANY, OF FORT WAYNE, INDIANA, A CORPORATION OF INDIANA.

VISIBLE DISPENSING APPARATUS.

Application filed December 30, 1925. Serial No. 78,318.

My invention relates to so-called visible dispensing apparatus and particularly to that adapted for use at filling stations in selling lubricating oil and other liquids.

The principal object of my invention is to provide a dispensing apparatus with transparent containers so lighted as to show the clarity or turbidity of oil and indicate its grade by its color.

10 A further object of my invention is, by the same lighting element, to keep the oil warm enough so that it will flow freely in cold weather.

A further object of my invention is to 15 provide means for lighting the portion of the apparatus where the operator is handling the measuring cans, by means of the same illuminating element heretofore spoken of.

A further object of my invention is to 20 provide a transparent display container substantially dust-proof, so that the containers which hold the oil and the lighting element will be kept clean at all times.

Another object of my invention is to 25 construct a device that may be completely closed up for purposes of protection against the weather and meddlesome persons, and at the same time and at all times leave the display portion in full view of the public.

30 A further object of my invention is to provide an apparatus capable of holding a plurality of different liquids or grades of the same liquid in the same dispensing apparatus, and keep a portion of each of these 35 liquids in full view of the prospective customers so that they may inspect the same and select the kind they want.

So far as the housing is concerned it may be of any convenient type but I prefer to 40 use that illustrated and described in my Patent No. 1,178,986 for housing for dispensing apparatus, issued April 11th 1916.

The particular embodiment of my invention selected for illustration is shown in the 45 accompanying drawings, in which

Figure 1 is an elevation of the complete apparatus with part of the casing broken away to show the means for counter-weighting the casing, a screen guard being provided 50 for the visible containers;

Fig. 2 is a vertical axial section, on a reduced scale, on lines 2—2 of Fig. 4, as though the device was there shown in full.

Fig. 3 is a cross section, on an enlarged 55 scale, on line 3—3 of Fig. 1, and

Fig. 4 is a cross section, on an enlarged scale, on line 4—4 of Fig. 1.

Referring now to the drawings A is the base of the pedestal of a visible dispensing apparatus, a is the barrel of the pedestal, a¹ 60 is the top member which rests on the top of the barrel a, and a², a part of a¹, forms a support for the measuring cans and the catch basin for the drippings. Drippings are collected and drawn off by the pipe a³ through 65 the cock a⁴. The barrel portion of a is clamped securely in position by the tie-rods a⁵ between the base A and the top member a¹. A vertical slidable outer casing member a⁶ is counter-balanced for easy raising and 70 lowering by means of the weights a⁸ and chains a⁷, which pass over sheaves a⁹ journaled in the top member a¹. The tie-rods a⁵ act as guides for the weights a⁸. One end 75 of the chain a⁷ is secured to the weight a⁸ and the other to the bottom of the slid- able casing member a⁶.

There are guide ribs a¹⁰ on the barrel a for the slidable casing a⁶. The slidable casing a⁶ has a suitable handle a¹¹ and a lock a¹² to 80 secure a⁶ in closed position.

Threaded into suitable holes a¹³ in the top member a¹ are pipes b, which act as supports for the casing cap B and fit into sockets b¹ 85 therein. Tie-rods b² pass upwardly through the washers a¹⁴ and the pipes b and are screwed into threaded holes b³ in the cap B. Said pipes b and tie-rods b² hold said cap B in suitably spaced relation to said top mem- 90 ber a¹, and form the measuring can compartment of the apparatus. The slidable casing member a⁶ when raised (which is in closed position) seats under the flange b⁴ of the cap B, to which it is locked by lock a¹². 95

A glass cylinder C seats on the cap B, and upon it the dome D rests, and the dome and glass cylinder are held securely in position together by the tie-rods c. A wire screen c¹ protects the glass casing C.

An electric wire conduit E extends up- 100 wardly through the whole apparatus and carries the incandescent light globe e, which is placed between the four glass reservoirs c². A glass disc b⁵ closes an opening in the center of the floor of the cap B and allows 105 light to shine downwardly and illuminate the measuring can compartment between the top member a¹ and the casing cap B.

A pipe c³, adapted to supply oil from a 110 source of supply not shown such as an un-

derground tank, extends upwardly through the casing, through one of the pipes b and into the glass cylinders c^2 , delivering the oil through opening c^4 . There is one such pipe c^3 for each cylinder and two such pipes pass upwardly through each pipe b . Each cylinder c^2 has a cover c^6 , and the cylinder is securely held in position by a tie-rod c^7 and cap nut c^8 .

10 10 The oil is drawn out of the cylinder c^2 through pipe c^9 , which preferably extends to near the top of said cylinder so as to maintain a body of oil in the cylinder c^2 , and the oil flows thence through valved nozzle c^5 into 15 measuring cans of any sort.

The oil is forced from the storage containers (not shown) to the cylinders c^2 in any usual or convenient manner as by air pressure.

20 20 It will be seen that the structure forms a convenient, secure and weather-proof apparatus, that shown being adapted to handle four kinds or grades of liquids, as for instance two grades of lubricating oil, alcohol, 25 and glycerine or other anti-freezing liquids.

I do not wish to be limited to the precise form of lubricating apparatus herein shown and described but claim as within the scope of my invention any apparatus readable 30 upon the claims which shall finally be allowed hereon.

I claim as my invention and desire to secure by Letters Patent of the United States:

35 1. A liquid dispensing apparatus comprising a portion having a transparent casing wall, a plurality of separate transparent liquid containers within the section enclosed by said transparent casing, lighting means

within said section adapted to light and 40 warm said liquid containers, a transparent floor for said section so that the downwardly projected rays from said lighting element may illuminate the space below and a valved nozzle within said space for each of said 45 containers.

2. In combination with a liquid dispensing apparatus, a plurality of independent transparent liquid containers parallel to each other, means for supplying liquid to 50 said containers and means for dispensing the liquid therefrom, a casing surrounding and entirely enclosing said containers, the wall and floor of said casing transparent, and an incandescent light between said containers 55 illuminating and heating the liquid contained therein.

3. In combination with a liquid dispensing apparatus, a plurality of independent transparent liquid containers in close proximity to each other, a transparent casing enclosing said containers and incandescent means between said containers and inside of 60 said casing, illuminating and heating the liquid in said containers.

4. In combination with a liquid dispensing apparatus, a plurality of independent transparent liquid containers in close proximity to each other, a transparent casing enclosing said containers, incandescent means between said containers and inside of 65 said casing, illuminating and heating the liquid in said containers, and separate valve means 70 for withdrawing liquid from each of said containers.

In testimony whereof I have hereunto set my hand.

LINNAEUS E. BAKER.
